CEMENT BAILER

Filed Nov. 29, 1922 2 Sheets-Sheet 2

UNITED STATES PATENT OFFICE.

LEE CLAYTON, OF MARICOPA, CALIFORNIA.

CEMENT BAILER.

Application filed November 29, 1922. Serial No. 603,965.

To all whom it may concern:

Be it known that I, LEE CLAYTON, a citizen of the United States, residing at Maricopa, in the county of Kern and State of California, have invented certain new and useful Improvements in Cement Bailers, of which the following is a specification.

The present invention relates to a device for cementing wells, when water breaks through into the well.

One object of the invention is to provide a device of this class, that is of very simple construction, and which accordingly does not easily get out of order. It is intended to convey the cement from the top of the well casing, when it is filled, to the bottom thereof and is for this purpose attached to the sand line. The bailer, after once being filled, operates automatically, that is to say, it opens in striking the bottom of the well and is in this manner emptied.

In the accompanying drawings, one embodiment of the invention is illustrated, and

Figure 1 shows the bailer assembled to proceed in downward direction in the well;

Figure 2 is a similar view to Figure 1, showing the relative position of the parts in the bailer, when traveling upwardly in the well;

Figure 3 is a longitudinal section along line 3—3 of Figure 1;

Figure 4 is a transverse section along line 4—4 of Figure 3, and

Figure 5 is another transverse section along line 5—5 of this same figure.

The bailer consists of a carrier or bucket 10, which preferably is made of an iron tube closed at its bottom, as at 11. Near the bottom are provided two windows or delivery openings 12 placed diametrically opposite each other. The upper end of the bucket 10 is threaded, as at 13, and a muff 14 connects this end and the top or suspending pipe 15 of the bailer. This top end has a loop 16 intended to receive the end of a sand rope 27 for hauling the bailer up and down the well casing. Between the bucket 10 and the top member 15 may be inserted any number of tubular connections, depending on the depth of the well.

The lower end of the bucket 10 is surrounded by a sleeve 17 adapted to slide up and down on the bucket. This sleeve has one or more helical slots 18 in its cylindrical

side, in which a stud 19 is adapted to travel, this stud being firmly secured near the bottom 11 of the bucket 10, as best seen in Figures 3 and 5. The helical slot terminates at the lower end with a notch or pocket 20 situated in the axial plane of the sleeve and directed upwards.

The sleeve 17 is also provided with windows 21 corresponding to those furnished in the bucket 10 and so positioned, that when the stud 19 is at the bottom of the helical slot 18 the windows 12 and 21 register, while, when the stud is at the top of the slot 18 the windows 12 in the bucket 10 are closed by the cylindrical wall of the sleeve 17, as seen in Figure 3.

The lower end of the sleeve 17 is preferably restricted, as at 22, and adapted to receive a nipple 23, threaded into the end of the sleeve. The function of this nipple 23 is to furnish a striking member for the bottom of the well and the reason for making the diameter at 22 smaller than the main diameter of the sleeve and the nipple still smaller in diameter, is to permit the easy retraction of the bail from the well, as it is evident that the bottom end of the nipple, by constant hammering against the well bottom, will gradually be upset and expand. When the nipple 23 has been worn or upset too much, it may then be replaced by a new one.

The sleeve 17 is provided with a pair of apertures 24 directly above the nipple for the passage of water or mud, so that the sliding up and down of the bucket 10, by this means, will not be obstructed.

The use of the bailer is as follows:

The sand rope 27 is tied to the loop 16 at the upper end of the bailer and, with the latter suspended at the top of the well casing, the bucket 10 is filled with cement. The sleeve 17 is now in the position shown in Figures 1 and 3, closing the windows 12 of the bucket 10 and the upper end of the helical slot 18 engaging with the stud 19. The bailer is now lowered into the well, as seen in Figure 1, until the nipple 23 strikes the bottom of the latter. The sleeve 17 is thereby arrested and the weight of the bucket 10 together with the attached top 15 and the intermediary tubing, continues its downward travel, while at the same time receiving a slight turning movement through the ac-

tion of the stud 19 in the helical slot 18. When the stud 19 nears the bottom end of the slot, the windows 12 and 21 will register, thereby permitting the cement contained in the bucket to fall out through the windows. By slightly raising and lowering the bucket 10, all the cement contained therein will gradually be dumped out of the windows 12 and 21. Finally the bucket is withdrawn by pulling on the rope 27, when it is evident that instead of following the helical slot 18, the stud 19 will travel in a perpendicular direction until engaging in the seat or notch 20 at the lower end of the slot, so that the sleeve 17, in this manner, is hauled up with the bucket 10.

It should be noted that the distance between the muff or collar 14 and the upper end of the sleeve 17, when they are furthest apart, as seen in Figures 1 and 3, is slightly less than the perpendicular length of the helical slot 18. This is for the purpose that the stud 19 or the edge of the slot 18 may not be injured or upset by the hammering of the bailer when hitting the bottom of the well. The adjacent faces of the muff 14 and the sleeve 17 are therefore made to come in contact before the stud 19 reaches the bottom of the slot 18, the hammering in this manner being taken up between the two wider surfaces instead of the two narrow ones.

When the bailer is hauled up after delivering the cement at the bottom of the well, it is evident that water and gravel may readily pass through the side openings 24 furnished in the sleeve 17 as well as through the axial aperture 25 in the nipple 23, and that in this manner every obstruction to the free and automatic operation of the bailer is removed.

As there is nothing to get out of order in this device and as the construction is extremely simple, the correct functioning of it is insured and the cost of manufacture is very low.

At times it might be desirable to insert a coil spring 29, see Figure 3 of the drawings, in order to prevent the sliding upwardly of the sleeve 17 during the descent of the bailer and thereby open the windows 12. With the spring 29 in place, no such opening can occur until the point of the nipple 23 hits the bottom.

At times, also, one or more packing rings 30 may be placed in suitable grooves in the bucket 10. These packings fit snugly in the bore of the sleeve 17. Such packing rings will then prevent the cement from leaking into the space between the sleeve and the bucket above the windows and adhering to the opposed walls so as to bind the parts together and prevent the necessary relative movement. It is evident that the device will operate whether such packings and

springs are furnished or not, but the right is reserved to include them in the construction of the device, when found necessary. The packing rings may be made of steel or, so-called hydraulic packing, in accordance with the requirements.

Having thus described the invention, what is claimed as new is:

1. A bailer of the class described comprising a bucket having side windows, a sleeve surrounding said bucket and provided with corresponding windows in its side normally displaced relative to the windows in the bucket, the sleeve also having a helical slot in its side and a downwardly opening notch in the upper wall of said slot at the lower end thereof, and a lateral stud on the side of the bucket playing in said slot whereby to effect rotation of the sleeve during axial movement thereof, said stud being adapted to seat in said notch upon upward movement of the bailer.

2. A bailer of the class described comprising a bucket having side windows, a sleeve surrounding said bucket and provided with corresponding windows normally displaced relative to the first-mentioned windows, means permitting axial and rotary displacement of the sleeve upon the bucket in order to cause the windows to register, and a hollow lower terminal for the sleeve below the bucket provided with transverse drain passages.

3. A bailer of the class described comprising a bucket having side windows, a sleeve slidably fitting around the bucket and provided with corresponding windows, the sleeve extending below the bucket and having a contracted lower end, an extension spring enclosed in the sleeve and bearing at its opposite ends against the restricted lower end of the sleeve and against the bottom of the bucket, and means permitting relative axial and rotary movement of the sleeve upon the bucket whereby to cause the windows to register and permit discharge from the bucket.

4. A bailer of the class described comprising inner and outer telescoping members, said members being provided with corresponding side windows, means on said members permitting a limited axial and revolving movement between them, thereby causing said windows to register when the overall length of the bailer is shortest and causing the windows to close when said length is greatest, said means including a locking device between said members when in their shortened position.

5. A bailer of the class described comprising inner and outer telescoping members, said members being provided with corresponding side windows, means on said members permitting a limited axial and revolving movement between them, thereby

causing said windows to register when the overall length of the bailer is shortest and causing the windows to close when said length is greatest, said means including a locking device between said members when in their shortened position, one of said members having a replaceable striking ele-

ment adapted to arrest said member when meeting an obstruction, while permitting the other of said members to continue its axial travel.

In testimony whereof I affix my signature.

LEE CLAYTON. [L. S.]
